(57) **CLAIM**

The ornamental design for an exercise block, as shown and described.

DESCRIPTION

FIG. 1 is a top-front-right perspective view of our new design, of which a bottom-rear-left perspective view is identical, which are left-right, top-bottom, and front-rear mirror symmetrical;

FIG. 2 is a front elevation view thereof, of which a rear elevation view is a mirror image;

FIG. 3 is a top plan view thereof, of which a bottom plan view is a mirror image;

FIG. 4 is a left elevation view thereof, of which a right elevation view is a mirror image;

FIG. 5 is a cross-section thereof taken along line 5-5 illustrated in FIG. 2; and,

FIG. 6 is a cross-section thereof taken along line 6-6 illustrated in FIG. 2.

The broken lines illustrate portions of the exercise block which form no part of the claimed design.

1 Claim, 3 Drawing Sheets
